UNITED STATES PATENT OFFICE.

WILLIAM PANCRAS HAMLYN, OF RUGBY, ENGLAND, ASSIGNOR TO GENERAL ELECTRIC COMPANY, A CORPORATION OF NEW YORK.

CIRCUIT-BREAKER.

1,010,422.

Specification of Letters Patent.

Patented Dec. 5, 1911.

Application filed November 30, 1907. Serial No. 404,621.

To all whom it may concern.

Be it known that I, WILLIAM PANCRAS HAMLYN, a subject of the King of Great Britain, residing at 59 Manor road, Rugby, in the county of Warwickshire, England, have invented certain new and useful Improvements in and Relating to Circuit-Breakers, of which the following is a specification.

10. This invention relates to improvements in electric switches, particularly automatic electrical circuit breakers of the type which are free to operate while the handle is held by the operator.
15. The object of my invention is to provide a simple and reliable mechanism the use of which makes it impossible for an operator to hold an electrical circuit closed either accidentally or intentionally should the conditions be abnormal such as where an overload, reverse or minimum current is passing in the circuit.
20. 25. 30. 35.

My invention is preferably embodied in a circuit breaker of the free handle type having a collapsible mechanism through which the circuit breaker is operated the said mechanism forming in the closing and closed positions of the circuit breaker a collapsible closed polygon of which the contact carrying arm or a part integral therewith is one of the sides the mechanism being prevented from collapsing and allowing the circuit breaker to open independently of the position of the closing mechanism by some restraining means, such as a catch, which acts preferably through a lever connected to one of the corners of the polygon.

According to my present construction and arrangement I use a toggle mechanism which is often used for this purpose and combine with it a special mechanical arrangement of levers which forms with the contact carrying arm a closed triangle by means of which the release can be effected with a small effort, whether the circuit breaker is in the closed position or in the act of being closed by the operator. On the main moving lever which carries the contact brush I pivot a bell-crank controlling lever or link having a long arm with its free end in a convenient position to coöperate with suitable latching means which normally prevent relative movement between the main lever and the controlling lever. On this specially shaped bell crank lever I pivot one end of another lever which I may call the intermediate le-

ver and I connect this lever at a suitable point preferably near to that at which the above mentioned special bell crank lever is pivoted on the main lever and at such a point that the downward pressure is as small as possible but sufficient to allow the arm of the controlling lever to swing from right to left when the circuit breaker is in the closed position or in the act of being closed when the catch is tripped. The other end of the intermediate lever is free but adapted to rest against a suitable fulcrum, such as a projection on the main lever, when the circuit breaker is closed or in the act of being closed, down which it can slide or roll when the retaining catch is tripped. At a suitable point between the fixed and free ends of the intermediate lever I connect one end of a toggle link the other end of which is fixed to the operating handle to form an ordinary toggle mechanism by which the circuit breaker is operated.

In the drawing, Figures 1 and 2 show a circuit breaker in sectional elevation fitted with my improved arrangement of levers in the open and closed positions. The dotted position of the levers in Fig. 2 indicates the position of the levers after the handle has been depressed to bring the long arm of the controlling lever back till it is held up by the trip catch ready for the circuit breaker to be closed again after it has operated. Fig. 3 shows the circuit breaker in plan view with the handle lever and spindle removed and Fig. 4 shows the position of the levers immediately the trip catch is released and just before the circuit breaker opens.

The main lever A is pivoted to a suitable stationary part at H H and is bifurcated as shown in Fig. 3. This lever A carries the bridging contact or main brush P as well as the auxiliary brush which, when the breaker is closed, make contact with the stationary contacts R to complete the circuit. Pivoted to the main lever A at J J is a bell crank controlling lever B M, the long arm M of which extends downwardly and in its extreme right hand position Fig. 1 is retained by a catch F. The bifurcated controlling lever B M carries a spindle K upon which is pivoted the intermediate lever C carrying a roller S at its lower extremity which engages a downwardly projecting part A' parallel to and integral with the main lever A and when the circuit breaker is opened this

roller travels over the projection or cam L formed on part A' of lever A and acting as a stop or fulcrum for the lower end of the intermediate lever. Pivoted to the intermediate lever C at T is a toggle link D which in turn is pivoted to the extension E of the handle Z rotatably mounted at V. Y is a fixed stop engaged by the extension E when the toggle is overset and the catch F is arranged so that the core O of a solenoid may be moved upwardly to trip the lever M.

In the closing and closed positions of the circuit breaker it will be seen by reference 15 to Fig. 1 the part A' part B and lever C form a triangle which may become distorted or collapsed to allow the circuit breaker to open by sliding of roller S downwardly along the cam surface on the part A' but 20 is prevented from so doing by the catch F acting on the lever arm M.

If a sudden overload occurs when the circuit breaker is being closed or is in the closed position the core O of the solenoid 25 will trip catch F allowing lever M to swing inwardly. This movement is caused by the pressure of the resilient brushes P and X acting on the levers with the point T as fulcrum. This motion is assisted by the 30 weight of parts acting at the point K and consequently as the arm M swings back intermediate lever C will descend carrying with it link D until pivot T is well over the dead center of the toggle system. As 35 lever C descends its roller slides around the projection or cam L and as soon as it slips behind said projection the end of the intermediate lever can move independently of the main lever A, and the brushes P and 40 X will be released, irrespective of whether the handle Z is held or not. To close the circuit breaker the first step is to depress handle Z whereupon the lever or extension E raises the intermediate lever C through 45 the medium of link D thereby bringing the arm M into the position where it is retained by catch F and the roller S back into position in front of lever A. The handle Z is then moved upwardly and owing 50 to the lever M being held by catch F the levers A, B and C act as a rigid lever to hold the brushes in position and are maintained closed by simply raising the handle to a sufficient extent to cause pivot N to 55 pass the dead center of the toggle system. In this position farther upward movement of the handle is arrested by stop Y. If during the closing of the breaker the catch F is tripped the parts will resume the open 60 position and it will be impossible to close the breaker while abnormal conditions obtain in the circuit.

What I claim as new and desire to secure by Letters Patent of the United States, is:—

65 1. An electric switch comprising an ac-

tuating member, a contact member, and a normally positive collapsible connection between said members comprising an intermediate lever connected to said actuating member to move therewith, restraining means for preventing the end of said lever being moved by the thrust of said actuating member when said lever is in normal position, connections between said lever and said contact member for transmitting the thrust of said actuating member to said contact member, and for permitting said lever to move relatively to said contact member until the end of said lever is free from said restraining means and can move independently of said contact member in response to the thrust of said actuating member, and latching mechanism for normally holding said lever in normal position.

2. An electric switch comprising an actuating member, a movable contact member, an intermediate lever connected to said member, a stop co-operating with one end of said lever to normally prevent it being moved by the thrust of said actuating member during switch closing movement thereof, a controlling link pivoted to the other end of said intermediate lever and to said contact member and tending under the thrust of said actuating member to move said lever relatively to said movable contact and carry the end of said lever out of engagement with said stop thereby leaving said lever free to move independently of said contact, and latching means for normally holding said intermediate lever in position with its end against said stop.

3. An electric switch comprising a movable contact member, a stop on said member, a controlling link pivoted to said contact member, an intermediate lever with one end pivoted to said controlling link and the other end in engagement with said stop when in normal position and free of said stop when out of normal position, an actuating member connected to said intermediate lever, and latching means for restraining said link and thereby holding said lever in normal position.

4. An electric switch comprising a pivoted contact member, a stop on said member near the pivot thereof, an intermediate lever having one end normally in engagement with said stop, an actuating member connected to said lever, a controlling link pivoted to said contact member and to said lever and movable to carry the end of said lever into and out of registry with said stop, and latching means for engaging said controlling link to hold it in normal position.

5. An electric switch comprising a movable contact member, a controlling link pivoted at one end to said movable contact member, an intermediate lever pivoted to said controlling link and moved longitudi-

nally by movement of said controlling link about its pivoted end, latching means co-operating with the other end of said controlling link to normally prevent movement thereof about its pivoted end, whereby said intermediate lever is maintained in normal position, an actuating toggle connected to said intermediate lever, and a stop which prevents movement of one end of said lever by the thrust of said toggle when said lever is in normal position but releases the end of said lever when said lever moves longitudinally upon the release of said controlling link by said latching means.

6. An electric switch comprising a pivoted contact member, a stop mounted on said member near the pivot thereof and terminating in an inclined surface, a controlling link pivoted to said member eccentric to the pivot, an intermediate lever having one end connected to said controlling link and the other end in engagement with the inclined surface of said stop, an actuating member connected to said intermediate lever to exert a thrust to rotate said contact member about its pivot, and latching means co-operating with said controlling link to hold it in normal position and thereby prevent movement of the end of said intermediate lever along the inclined surface of said stop and out of engagement with said stop.

7. An electric switch comprising an actuating member, an intermediate lever connected to said actuating member, a stop for engaging the end of said lever when said lever is in normal position, a movable contact member, a bell crank connecting link pivoted at one end to said contact member and at the angle to said lever, said link being movable to carry the end of said lever out of engagement with said stop and there-

by free said members from each other, and latching means co-operating with the other end of said link to hold said link in normal position.

8. An electric switch comprising a movable contact member, an actuating toggle overset when the switch is closed, an intermediate lever connected to one end of said toggle, restraining means for holding one end of said lever immovable against the thrust of said toggle when said lever is in normal position, connections between said contact member and said lever for transmitting the thrust of said toggle and for permitting said lever to move relatively to said contact member to free the end thereof from said restraining means and to underset said toggle, and latching means for normally holding said lever with its end in engagement with said restraining means.

9. An electric switch comprising a movable contact member, an actuating toggle for moving said member, an intermediate lever connected to said toggle and mounted on said contact member to normally transmit the thrust of said toggle to said member and to move along said member transverse to the line of thrust of said toggle out of normal relation to said member and thereby permit said member to move independently of said toggle, and latching means for normally holding said lever against movement along said member.

In witness whereof, I have hereunto set my hand this nineteenth day of November 1907.

WILLIAM PANCRAS HAMLYN.
